UNITED STATES PATENT OFFICE.

WILLIAM F. MARKHAM AND ERNEST S. ROE, OF PLYMOUTH, MICHIGAN, ASSIGNEES TO
MARKHAM AIR RIFLE COMPANY, OF PLYMOUTH, MICHIGAN, A CORPORATION OF
MICHIGAN.

GUN.

No. 880,555.

Specification of Letters Patent. Patented March 3, 1908.

Application filed April 15, 1907. Serial No. 368,331.

To all whom it may concern:

Be it known that we, WILLIAM F. MARKHAM and ERNEST S. ROE, citizens of the United States of America, residing at Plymouth, in the county of Wayne and State of Michigan, have invented certain new and useful Improvements in Guns, of which the following is a specification, reference being had therein to the accompanying drawings.

10 The invention relates to improvements in guns, and more particularly to spring-actuated air guns of that type in which the spring is placed under compression by the operation of a lever.

15 It is the object of the invention to obtain a simple construction of actuating mechanism, and one which may be easily operated.

In the construction of spring-actuated air guns, it is usual to place the spring in a barrel 20 or housing, one end abutting against the air compression cylinder, and the other against a fixed abutment. The spring is placed under tension by drawing the compression plunger rearward, this being accomplished 25 by various forms of operating mechanism. One form of mechanism, which has heretofore been used, is a lever pivoted in the frame of the gun, and having one end thereof in engagement with a bearing on a rearwardly-

30 extending shank of the compression plunger. The opposite end of the lever extends normally adjacent to the stock of the gun, and in operation the movement of this end of the lever forward will cause the other end to 35 draw the shank of the plunger rearward, thereby compressing the spring. There is, however, a serious objection to such a form of operating mechanism, viz., that as the lever swings in the arc of the circle, it exerts a

40 lateral, as well as a longitudinal stress upon the plunger shank, which introduces a large element of friction and increases the work to be performed. The greater the angle through which the lever swings, the more

45 will be the frictional loss, and as the longitudinal movement of the plunger is considerable, and the space in which the lever may be arranged is limited, it is impossible to avoid a considerable angular movement.

50 With the present invention the difficulties, as above stated, are avoided by providing a lever having a plurality of points in engagement with the shank of the plunger. The arrangement is such that the lever in each of

55 its successive engagements exerts a stress

chiefly in the line of movement of the plunger, while the lateral movement of each bearing, incident to the angular movement of the lever, occurs while out of engagement. Thus, the element of friction is greatly reduced without decreasing either the length 60 of the movement of the plunger or the angular movement of the lever.

In the drawings, Figure 1 is a longitudinal section through a spring air gun provided 65 with my improved construction; Fig. 2 is a similar view, illustrating the operation. Fig. 3 is an elevation of the shank.

A is the barrel or casing, B the plunger, and C the spring, which at one end bears 70 against the plunger, and at its opposite end against an abutment D.

E is a shank extending rearward from the plunger, around which the spring C is sleeved.

F is a lever fulcrumed at G and normally 75 extending adjacent to the stock of the gun. The opposite end of this lever extends upward into proximity to the shank E. The engagement between the lever F and the shank E is formed by a plurality of lugs or 80 fingers at the inner end of the lever, which are adapted for successive engagement with the coöperating bearings upon the shank. As shown, the lever is provided with two 85 such fingers, H and I, which project into a longitudinal slot in the shank E, while the coöperating bearings J and K are formed by pins extending across the slot. The lug or finger H is so arranged that during the initial movement of the lever it will bear against 90 the pin J, and will draw the shank rearward for a portion of its travel. The lug or finger I extends at a different angle, and, in the first place, is out of engagement with its co-operating pin K. As soon, however, as the 95 lever has traveled a portion of its movement, the finger I will be brought into contact with the pin K, while the finger H will pass out of engagement with the lug J. The further movement of the lever will then complete 100 the rearward movement of the plunger until engaged with the trigger detent (not shown). The lever may then be returned to its initial position, the plunger remaining retracted and the spring under compression until the 105 gun is filled.

The shank E is preferably formed, as illustrated in Fig. 3, by a strip of sheet metal, which is bent to form the parallel side members *a b*, between which and the slot are 110

spaces into which the fingers II and I project. The pins J and K extend between these side members, and the forward ends of the sides are riveted or otherwise attached to 5 the plunger B.

- What I claim as my invention is:

1. In a gun, the combination with the 10 spring, the plunger and a shank inwardly-extending therefrom, of a rockable spring compressing member, and a plurality of co-operating bearings on the front end of said rockable member and shank arranged for successive engagement.

2. In a gun, the combination with the 15 spring, a plunger and a shank inwardly-extending therefrom, of a rockable spring compressing member, a plurality of bearings on the rear end of said shank and co-operating fingers on said rockable member extending at 20 different angles and arranged for successive engagement with their respective bearings.

3. In a gun, a plunger, retracting mechanism comprising a pivotal lever having furcations at one end thereof, and an inwardly-extending plunger shank having a plurality of 25 bearings at the rear end thereof for successive engagement with said furcations.

4. In a gun, the combination with a plunger, of a shank therefor formed of a pair of 30 separated side members, a pivotal lever having furcations extending between said side

members, and a plurality of pins extending between said side members arranged for successive engagement with said furcations.

5. In a gun the combination with a barrel, 35 of a spring, a plunger, a shank formed of a pair of separated side members longitudinally operable in axial alignment with said barrel, a pivoted member having a Y-shaped member at one end thereof, and a plurality of pins extending between said side members arranged for engagement with said Y-shaped member.

6. In a gun, the combination with the 40 spring and a plunger, of a shank formed of a pair of separated side members, a pivotal lever having a Y-shaped portion at one end thereof, and a plurality of pins extending between said side members arranged for engagement with said Y-shaped member.

7. In a gun, the combination with the 45 spring and a plunger, of a shank, a pivotal lever having a Y-shaped member at one end thereof and bearings on said shank arranged for engagement with said Y-shaped member.

In testimony whereof we affix our signatures in presence of two witnesses.

WILLIAM F. MARKHAM.
ERNEST S. ROE.
